UNITED STATES PATENT OFFICE

105,368

DESIGN FOR A TEXTILE FABRIC

Curt E. Forstmann, Montclair, N. J.

Application September 12, 1936, Serial No. 64,829

Term of patent 14 years

To all whom it may concern:

Be it known that I, Curt E. Forstmann, a citizen of the United States, residing at Montclair, in the county of Essex and State of New Jersey, have invented a new, original, and ornamental Design for Textile Fabric, of which the following is a specification, reference being had to the accompanying drawing, forming part thereof.

In the drawing, the sole figure of which is a plan view of a piece of the textile fabric embodying the design of the present invention, the cloth depicted is of a single color.

The design comprises a woven fabric resulting from a coarse loosely twisted special yarn in the weft, said fabric having warpwise extending wales in substantially regular rows, the width of the wales being about three times the width of the spaces between the wales, and the disposition of the stitches in the wales being irregular.

I claim:

The ornamental design for a textile fabric as described and as shown.

CURT E. FORSTMANN.
